(74) **Attorney, Agent, or Firm:** Eversheds Sutherland (US) LLP

(57) **CLAIM**

We claim the ornamental design for a waste receptacle, as shown and described.

DESCRIPTION

FIG. 1 is a front perspective view showing our new design for a waste receptacle;

FIG. 2 is a rear perspective view showing the waste receptacle of FIG. 1;

FIG. 3 is a front view showing the waste receptacle of FIG. 1;

FIG. 4 is a rear view showing the waste receptacle of FIG. 1;

FIG. 5 is a left side view showing the waste receptacle of FIG. 1;

FIG. 6 is a right side view showing the waste receptacle of FIG. 1;

FIG. 7 is a top view showing the waste receptacle of FIG. 1; and,

FIG. 8 is a bottom view showing the waste receptacle of FIG. 1.

In FIGS. 1 to 8, the broken lines in the figures are for purposes of illustrating portions of the waste receptacle, that form no part of the claimed design.

1 Claim, 7 Drawing Sheets
